UNITED STATES PATENT OFFICE.

EDWIN T. GREENFIELD, OF NEW YORK, N. Y.

PIPE-HOOK.

SPECIFICATION forming part of Letters Patent No. 651,482, dated June 12, 1900.

Application filed December 18, 1899. Serial No. 740,683. (No model.)

To all whom it may concern:

Be it known that I, EDWIN T. GREENFIELD, a citizen of the United States, residing at New York, borough of Manhattan, county and State 5 of New York, have made a new and useful Invention in Pipe-Hooks, of which the following is a specification.

My invention has for its object to construct a pipe-hook of a single piece of wire adapted 10 to be secured by a nail or screw in such manner as to make it possible to utilize the same in connection with the holding or securing of pipes to walls, ceilings, and in similar places, so that said hooks may be secured in place 15 under all conditions of usage with as little annoyance and discomfort as possible.

To this end my invention consists of a pipe-hook made of a single piece of wire and provided with a shank or standard adapted to 20 receive a holding nail or screw, and will be fully understood by referring to the accompanying drawing, which is a perspective view of the invention, illustrating its application to the holding or securing of a pipe, the latter being shown in dotted lines.

For a full and clear understanding of the invention, such as will enable others skilled in the art to construct and use the same, reference is had to the drawing.

25 To construct this form of pipe-hook, I take

a piece of steel wire and beginning at one end E wind the same spirally in the form of a coil around a mandrel of the desired diameter until a shank or standard S of sufficient length is constructed. I then form the body 35 part of the hook H in the manner shown, and finally secure the end E' above the shank or standard.

In using this form of the hook it is placed upon the pipe P, as shown, and a nail N 40 driven through the shank or standard S into the wall or surface to which said pipe is to be secured.

Having thus described my invention, what I claim, and desire to secure by Letters Patent of the United States, is—

A pipe-hook composed of a single piece of wire wound continuously in successive spiral coils so as to constitute a shank or standard, the continuation thereof being bent into the 50 form of a hook and back upon itself with the end bent over the rear portion of the hook, substantially as described.

In testimony whereof I have hereunto subscribed my name this 15th day of December, 55 1899.

EDWIN T. GREENFIELD.
